RADIATOR PRESSURE CAP

Bruce E. Clark and Gerald K. Vieson,
Dearborn, Mich.

Application February 23, 1949, Serial No. 77,708

6 Claims. (Cl. 220—44)

1

The present invention relates to a radiator pressure cap which is adapted to relieve both excessive pressures and negative pressures created within an engine cooling system utilizing a coolant liquid and a radiator.

Radiator pressure caps which have been developed previously to control pressure conditions in such a cooling system and to relieve conditions of excessive pressure and negative pressure have utilized two separate spring loaded valves. Such a construction is expensive and is not positive due to variations in the spring characteristics.

Therefore, a principal object of the present invention is to provide a radiator pressure cap which controls pressure within the radiator and which is simple in construction and contains a relatively small number of parts.

A further object of the present invention is to provide a radiator pressure cap which contains only one valve assembly to accomplish a pressure normalizing effect when either excessive or negative pressures exist in the cooling system.

Other objects of this invention will appear in the following description and appended claims, reference being had to the accompanying drawings forming a part of this specification wherein like reference characters designate corresponding parts in the several views.

In the drawings:

Fig. 1 is an elevation in section showing a radiator cap embodying the present invention attached to the filler spout of a radiator.

Fig. 2 is an elevation in section of the radiator cap of the present invention.

Fig. 3 is an elevation, partly in section, showing the position of the parts of the radiator pressure cap of the present invention when there is a negative pressure or partial vacuum in the cooling system.

Fig. 4 is an elevation, partly in section, showing the position of the parts of the radiator pressure cap of the present invention when there is an excessive pressure in the cooling system.

Before explaining the present invention in detail it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the drawings, the top chamber or header of a radiator is indicated by the numeral 10. A

neck 11 extends upward from the said header and connects with the filler spout 12. An annular bead 13 surrounds the opening in the top of the neck 11, and an overflow pipe or vent 14 leads from the filler spout 12 to the open air. The upper edge of the filler spout 12 is rolled over to provide the collar 15 in which are formed elements of the conventional bayonet lock (not shown) for detachably holding the radiator pressure cap in position.

The radiator pressure cap of the present invention consists of a cap 16 which is formed with a circular groove 17 and a centrally located spring seat 18. The cap 16 is also formed with a downwardly and inwardly extending flange 19 which is adapted to engage the overturned end of the collar 15 in a conventional locking engagement such as the bayonet type engagement which is well known in this art.

An upper cup member 20 is located in place over the guide member 21 formed by the annular groove 17 in the cap 16. The top part of the upper cup member 20 is formed into a downwardly extending resilient retainer member 22. This retainer member acts as a sealing gasket when in the position shown in Fig. 1. The lower part of the upper cup member 20 is turned to form the surface 23.

Extending through the bottom opening of the upper cup member 20 is the lower cup member 24. The lower cup member 24 is closed at its bottom, and flared at its top to provide the surface 25. A shoulder portion 26 is formed near the top of the lower cup member 24, and a plurality of holes or ports 27 are spaced around the circumference of the said lower cup member 24 near its bottom. A resilient stopper 28 is fitted around the lower portion of the lower cup member 24 and extends against the shoulder 26. A coil spring 29 is disposed between the spring seat 18 in the cap 16 and the bottom of the lower cup member 24.

Attachment

The radiator pressure cap shown in Fig. 2 is attached to a radiator in the position shown in Fig. 1 as follows:

The stopper 28 is inserted in the filler spout 12 and over the top opening of the neck 11. The stopper 28 seats against the bead 13. Force is exerted downwardly on the cap 16, the coil spring 29 is compressed, and the surfaces 23 and 25 separate to form the opening or gate 30. At the same time, the end of the resilient retainer member 22 contacts the collar 15 on the filler spout

12, thus closing and sealing the cap 16 under tension. In this position a sealed cooling system is provided so that none of the coolant escapes.

Excessive pressure condition

Fig. 4 demonstrates the position of the elements of the radiator cap of the present invention when there is excessive pressure in the cooling system of a vehicle. This condition may result in several ways. If the radiator is filled while the motor is cool, there is a natural expansion of the fluid when it is heated and when circulation begins. Another way in which the condition results is when the cooling system overheats and the coolant is converted to steam or vapor.

When the pressure in the cooling system exceeds a predetermined amount (determined by the pressure characteristics of the spring 29), the stopper 28 is forced upward against the tension of the spring 29 when compressed and is lifted clear of the bead 13 provided in the neck 11. With the stopper 28 thus raised, the excess pressure and vapor or coolant is allowed to escape along the path indicated by the arrows, Fig. 4, through the neck 11, past the stopper 28, and out the vent or overflow pipe 14. When the pressure in the cooling system is reduced below the predetermined amount required to lift the stopper 28 against the tension of the spring 29, the stopper 28 returns under tension of the spring 29 to the closed position.

Negative pressure condition

When the coolant has once been heated and then the coolant and cooling system is allowed to cool, a partial vacuum or negative pressure is created in the cooling system which, if not released, might bring about a collapse of the radiator header. When this condition prevails, the elements of the radiator pressure cap of the present invention are in the position shown in Fig. 3.

The unequal pressures inside and outside the cooling system cause the lip 31 of the stopper 28 to be forced away from the lower cup 24 as indicated in Fig. 3. This action uncovers the holes or ports 27, and the outside air follows the path indicated by the arrows, Fig. 3, through the vent or overflow pipe 14, the opening or gate 30, the ports 27, and the neck 11 into the cooling system. When the pressure within the cooling system returns to normal, the lip 31 of the stopper 28 returns to the normal position and covers the ports 27.

The hardness of the rubber or other resilient material of which the stopper is made and the thickness of the section of such material are relied upon to regulate the pressure differential at which the lip will be forced away from the vacuum relief ports 27 to admit air from the vent 14 and filler spout 12 to satisfy the vacuum within the cooling system at a point below which the radiator header 10 will collapse. Depending upon the structure of the radiator header 10, this is generally found to be in the neighborhood of ten pounds.

Referring to Fig. 2, it will be noted that the surfaces 23 and 25 are in contact under tension of the spring 29 when the radiator pressure cap is removed from the filler spout 12 of a radiator. This construction prevents dirt and foreign matter from accumulating in the interior construction of the device.

The spring 29 is a low rate spring. That is,

it is a spring which has a low rate of change in tension as it is compressed. The device of the present invention is designed to permit use of a relatively long spring which aids in establishing such a low rate. This enables the spring to exert as nearly as possible a constant force throughout the movement of the plug or stopper 28, and enables the said stopper to reset promptly after the blow off pressure is relieved. The device of the present invention has been so designed that when manufactured to usual manufacturing tolerances, the cap will hold the pressure within limits of approximately one pound variation.

Thus, it will be seen that the present invention provides a simple and efficient radiator pressure cap which will effectively and closely control the pressures in a cooling system within predetermined limits. A feature of importance in a cap of the present invention is the ease of installation and replacement of the resilient stopper 28. As will be seen, this stopper is held in place at the top by the shoulder 26, but is removable from the cap by a pull in a downward direction. Thus, if the stopper becomes worn or loses its resiliency it may readily be removed from the cap and replaced by a new resilient stopper ring and the cap thus restored to its original usefulness.

Having thus described our invention, we claim:

1. In a cooling system, a filler spout provided with a seating bead around the lower opening thereof, a neck communicating with the lower opening of said filler spout, a vent or overflow pipe leading from said filler spout, a closure member removably connected to said filler spout and comprising a cap, means to lock said cap to said filler spout, a hollow telescoping cup member extending downwardly from said cap and having circumferentially spaced holes near the bottom thereof, a spring interposed within said cup member between said cap and the bottom of said cup member, a resilient stopper surrounding the lower portion of the said cup member and normally covering the holes therein and movably seating on said seating bead.

2. A device as claimed in claim 1 and further characterized in that a shoulder portion is formed on the said cup member to prevent the stopper from moving upwardly out of place.

3. In a radiator pressure cap of the type wherein pressures within a radiator are controlled by valve means disposed within a hollow cup member communicating with the open air and extending into the filler spout of a radiator, a combined excessive pressure and vacuum relief valve comprising a hollow telescoping cup member extending downwardly from a closure member and having spaced holes in the lower portion thereof, a spring interposed between the said closure member and the bottom of said cup member, and a resilient stopper movably seated on the opening at the bottom of the filler spout, said stopper being disposed around said cup member and having a lower portion relatively thin in cross section covering the said holes in the normal position whereby said portion will move to open the said holes when the pressure of the atmosphere exceeds by a predetermined amount the pressure within the radiator.

4. A device as claimed in claim 3 and further characterized in that a shoulder portion is formed in the side wall of the said cup member above said spaced holes to prevent the stopper from moving upwardly out of place.

5. A device as claimed in claim 3 and further characterized in that the said resilient stopper is

formed in the shape of an inverted truncated cone which extends into the opening in the bottom of the said filler spout in the seated position.

6. A radiator pressure cap of the class described comprising a closure member, an upper and a lower cup member in telescoping engagement and extending downwardly from said closure member, said lower cup member having circumferential holes near the bottom thereof and a shoulder formed above said holes, a spring disposed within said cup member, a resilient stopper disposed around the lower cup member and against the shoulder provided therein and normally covering the said holes in the lower cup member, and surfaces formed near the bottom of the upper cup member and the top of the lower cup member which provide a gate and which closes when the

cap is free from a radiator and which opens when the cap is in its attached position.
